(57) **CLAIM**

The ornamental design for a rocker arm assembly, as shown and described.

DESCRIPTION

FIG. 1 is a perspective view of a rocker arm assembly showing the new design.

FIG. 2 is a top view of the rocker arm assembly of FIG. 1.

FIG. 3 is a bottom view of the rocker arm assembly of FIG. 1.

FIG. 4 is a first side view of the rocker arm assembly of FIG. 1.

FIG. 5 is a second side view of the rocker arm assembly of FIG. 1.

FIG. 6 is a first end view of the rocker arm assembly of FIG. 1; and,

FIG. 7 is a second end view of the rocker arm assembly of FIG. 1.

The broken line showing portions of the rocker arm assembly form no part of the claimed design.

1 Claim, 6 Drawing Sheets
